US0D1087917S

(12) **United States Design Patent** (10) **Patent No.:** **US D1,087,917 S**
(45) **Date of Patent:** **** Aug. 12, 2025**

(54) **ELECTRICAL CONNECTOR PLUG**

(71) Applicant: **Changzhou Chaoyisheng Electronic Technology Co., LTD**, Changzhou (CN)

(72) Inventor: **Zhiyi Wang**, Changzhou (CN)

(**) Term: **15 Years**

(21) Appl. No.: **29/874,179**

(22) Filed: **Apr. 14, 2023**

(51) **LOC (15) Cl.** **13-03**

(52) **U.S. Cl.**

USPC **D13/146**

(58) **Field of Classification Search**

(57) **CLAIM**

The ornamental design for an electrical connector plug, as shown and described.

DESCRIPTION

FIG. 1 is a front elevation view of an electrical connector plug showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is another perspective view thereof; and,

FIG. 9 is a perspective view of the electrical connector plug in an open state.

The broken lines depict portions of the article that form no part of the claimed design.

1 Claim, 9 Drawing Sheets
